Application September 10, 1938, Serial No. 229,314

5 Claims. (Cl. 18—17)

This invention, as indicated, relates to an automatic combined heating and compressing apparatus. More particularly, it comprises an apparatus to subject material placed therein to predetermined conditions of pressure and temperature. The apparatus is of particular utility in connection with the closing of dental flasks having therein synthetic material, such as Bakelite, preliminary to the curing steps in the production of such plastic structures.

Heretofore it has been the practice in various lines of manufacture, and particularly in dental laboratory procedure, where pressure was to be applied progressively in connection with certain temperature conditions, to apply such pressure manually after checking the temperature of the material in the course of processing. Such manual adjustment has involved lack of uniformity of control and is not conducive to precision or to the attainment of dependable and uniform results in the product resulting from the operation.

The principal object of the invention is to provide an apparatus for progressively applying pressure to material to be conditioned under certain predetermined amounts of heat and pressure over a fixed period.

Another object of the invention is to provide an apparatus adapted to apply heat to material to be subjected to pressure and maintain such heat at a predetermined amount together with the application of pressure to such material progressively over a predetermined length of time to attain certain uniform characteristics in the material undergoing treatment.

Another object of the invention is to provide a press adapted to operate upon one or more material supporting elements to maintain heat within a range of a predetermined amount and to progressively apply pressure thereto uniformly over a period of time so as to produce certain predetermined characteristics in the material undergoing treatment.

Another object of the invention is to provide a press having one or more movable platens and a fixed abutment with means for heating one or more of said platens and imparting such heat to the material undergoing treatment and means for progressively moving one or more of said platens so as to apply pressure thereto progressively over a predetermined range of movement.

Another object of the invention is to provide a press having one or more movable platens and a fixed abutment for receiving material to be treated and moving said platen or platens at a predetermined rate of movement so as to apply pressure to the material being treated progressively with means for discontinuing such pressure at a predetermined point and with means additional to the pressure applying means for releas-

ing the pressure after a predetermined limit has been reached.

Another object of the invention is to provide a press with transmission and motor assembly and switch control for said motor, such switch being adjustable for actuation at a predetermined point of motion of said press and operating with means for releasing said press independently of said pressure applying means.

10 Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain mechanism embodying the inventions, such disclosed means constituting, however, but several of various forms in which the principle of the invention may be used.

20 In said annexed drawing:

Fig. 1 is a side elevation partly in section showing an apparatus embodying the principles of the invention, as seen along the lines 1—1 indicated in Fig. 2;

25 Fig. 2 is a fragmentary plan view partly in section, as seen along the lines 2—2 looking in the direction of the arrows; and

Fig. 3 is a fragmentary front elevation of the 30 switch mechanism, as seen along the lines 3—3 shown in Fig. 1 looking in the direction of the arrows.

As is clearly shown in Fig. 1, the apparatus comprises a base plate 1 upon which is supported a press structure 2, a transmission 3 and a motor 4, the parts being so related to each other as to transmit power from the motor to the press at a very low ratio to the end that a very slow but uniform rate of movement will be transmitted 35 to the movable members of the press. The press may assume various forms, but in the structure illustrated comprises a frame with four equally spaced standards 5, said standards being of larger diameter over their lower range of extent and having shoulders 6 at their upper ends serving as limit stops for the lowermost platen or movable abutment 7 which is engaged upon intermediate portions 8 of the standard of 40 slightly less diameter than the lower section. The intermediate sections 8 in turn have shoulders 9 serving as limit stops for the uppermost platen or movable abutment 11 which slidably 45 engages the uppermost sections 12 of the standards which are of lesser diameter than the intermediate sections, said uppermost sections 12 of the standards are provided at their upper ends with shoulders 13 against which the top plate or fixed abutment 14 of the press is engaged, said 50 plate being held in position by means of nuts 15

engaged over screw-threaded terminal portions 16 at the upper ends of the standards.

While two platens have been shown in Fig. 1 it is to be noted that the uppermost platen shown may be omitted, or that a series of upper platens similar to the platen or movable abutment 11 may be provided at the upper portion of the press in accordance with the requirements of the work in hand. Where two movable platens are provided as shown in Fig. 1 when but a single space of the press is required for the material, in this instance a dental flask 11, the upper space may be provided with a pressure distributor element 18 in the form of a steel tubular member of a size to approximately fill the area between the standards of the press and distribute the pressure adjacent the margins of the uppermost platen and the fixed abutment of the press.

The standards, in place of being provided with shoulders at intervals to serve as spacing or limit stops for the platens, could be made of uniform diameter throughout and be provided with collars or other means for spacing the movable elements engaged upon such standards.

In the apparatus shown each of the platens or movable abutments 7 and 11 is provided with a heating element 21 in the form of an annular coil of suitable resistance material 22 engaged within suitable insulating material 23. The circuit connections 24 for the coils are suitably insulated by means of nipples 25 from contact with the platens and may each be provided with suitable thermostats for maintaining uniform heat in each of the respective platens. Such thermostats may be adjustable so that any required degree of heat may be provided for the type of material undergoing modification.

The upper platen or movable abutment 11 has a plane upper and lower face while the lowermost platen is provided with a plane surface on its upper side and has centrally of its under side a boss 26 countersunk to provide a socket 27 to receive the shaft 28 of the press, and also countersunk to provide a recess 29 to receive the upper end of a coil spring 31. The coil spring is housed within a recess 32 provided in the upper end of the shaft 28, and is normally of a length and of a stiffness to hold the lowermost platen or movable abutment 7 in slightly spaced relation to the upper end of the shaft 28, but is responsive to the higher pressure when the flask is closed and the limit of motion of the apparatus is reached so as to be slightly compressed and permit the shaft 28 to move further into the recess in the boss 26. This relative movement of the shaft to the lowermost platen is sufficient in degree to operate the switch controlling mechanism as will be herein-after described. The shaft 28, it will be noted, is formed with an enlarged cylindrical upper portion terminating in a conical section 33 serving as a hub for an adjusting wheel 34 frictionally engaged therover and also locked thereto by means of a set-screw 35 extending at an angle through a socket 36 in the hub of said adjusting wheel 34 provided with four spokes 37 which are provided with radial sockets 38 opening through the rim of the adjusting wheel 34 and adapted to receive a locking bar 39 having a reduced shank portion 40 to engage the socket 38. By means of the locking bar 39 bearing against one of the standards 5, the turning movement of the shaft 28 is prevented, but there is no interference with the sliding movement of such shaft as the shaft 28 is advanced upwardly to apply pressure

to the underside of the platen or movable abutment 7.

The means for applying pressure to the apparatus through the under side of the lower platen or movable abutment 7 will now be described. The shaft 28, when locked against rotation by the locking bar 39 carried on the adjusting wheel 34, which in turn is non-rotatably fixed to the shaft, is free to slide vertically up or down. The means 10 for bringing about vertical movement of the shaft 28 comprises a gear driven collar 41 having an internally threaded central aperture 42 engaging a screw-threaded section 43 at the lower end of the shaft. The lower end of the shaft is 15 of reduced diameter, and is provided with an axial bore 44 extending from its lower end partly into the tapered section 33 heretofore referred to. The collar 41 has a disk like extension 45, carrying bevel gear teeth 46 on its under marginal area, such teeth meshing with a drive pinion 47 on the drive shaft 48 projecting from the 20 transmission unit 3 heretofore referred to, such unit in turn being connected with the power input shaft 49 of the unit having a pulley 51 with a belt drive 52 from a pulley 53 on the shaft 54 of the electric motor 4 which may be supported on the base 1 by a bracket 55.

The collar 41 and its disk extension 45 is rotatably supported on a central tubular member 61 30 firmly secured to the base 1 intermediate the standards 5 heretofore described. A thrust ball bearing assembly 62 is interposed between the base 63 on the underside of the collar and the upper end of the tubular member 61. Centrally 35 of the tubular member 61 a guide pin 64 is mounted, said pin slidably engaging within the bore 44 of the shaft 28 and extending to a point slightly above the plane of the top edge of the collar. The additional extent of the bore provides for an adequate range of downward movement of the shaft and the lower platen. A light metal sleeve 65 is provided above the collar to 40 protect the screw-threaded portion of the shaft.

The switch mechanism will now be described. 45 As shown more particularly in Figs. 1 and 3, the switch includes a glass tubular member 71 having terminals of the circuit conductors 72, 73 within one end of the same adapted to be closed or connected by a globule of mercury 74 when in normal 50 position, and to be opened when tilted as shown in Fig. 3.

The tubular element 71 is supported in a clamping member or frame 75, pivotally mounted on pin 76, carried by a supporting plate 77. The 55 supporting plate at its upper end is provided with a pair of elongated slots 78, through which are engaged adjusting screws 79 received in screw-threaded openings 80 in the outer face of the lower platen 7, thus permitting a shift in the position of the plate to any extent required in setting up the apparatus for any particular work. The lower portion of the plate 77 is bent to form a lower edge 81 of rectangular cross-section and is provided with aligned openings 82, 83, to receive a switch actuating pin 84 which bears at its lower end upon the top circumferential margin of the adjusting wheel 34, and at its upper end is normally slightly spaced from the frame 75 of the tubular switch element 71. The frame 75 is 60 preferably provided with an upwardly extending arm 85 with a terminal knob 86 for easy manual actuation.

It is believed the operation of the apparatus will be readily understood from the description 70 of its construction, but a brief summary will be

made to show the complete adjustment and operation of the apparatus as applied to the elements shown in Fig. 1.

The heating current is started in the upper and lower platens and the temperature checked. The shaft is reversed through the hand wheel to lower the platen or movable abutment 7 to the requisite extent, and the tubular spacing and pressure distributing member 18 is then engaged between the top plate 14 and the upper movable abutment or platen 11, if a second dental flask, or the like, is not to be placed in the apparatus. The single dental flask 17 is then engaged between the upper and lower platens. The flask as shown has notched guide members 90 of considerable height so as to guide the matched mold cavities in the preshaped mold material 91 in the respective mold halves. For synthetic plastic dental plates 92 of Bakelite, or the like, carrying artificial tooth units 93 in the drag it is customary to use metal foil lining for the mold cavity. This must not be broken or disturbed during the period of application of heat and pressure to the plate material in the mold cavity.

A careful adjustment of the flask between the platens or movable abutments is then made, and the switch plate is checked for proper setting to fix the timing of the end of the operation. The adjusting wheel 34 and the locking bar are placed in locking relation to one of the standards 5. The switch is then moved manually to starting position and the motor actuates the drive mechanism to elevate the lower platen or movable abutment. The low gear ratio brings about a very gradual closing of the flask and the platens or movable abutments are held meanwhile at proper temperature by their respective thermostats. The closing movement of the apparatus must continue until the flask is completely closed. If no provision was made to continue the pressure past the closing point there would be danger of an incomplete closing movement or of the locking of the driving mechanism. The compressible spring and its associated elements fully take care of either of these contingencies, as the mechanism is not stopped until the closing point is well passed. As the flask sections are brought into firmly closed relation, the spring 31 must take up the thrust of the shaft 28 and as the spring is compressed, the adjusting wheel rim forces the pin 84 upwardly tilting the tubular switch element 71 to bring the mercury globule to the non-circuit closing position shown in Figure 3. When the operation is thus terminated, the flask, or other element, may be readily removed by withdrawing the locking bar 39 from its socket and reversing the rotation of the adjusting wheel 34. The pinion 47 engaging the disk extension 46 prevents the collar 41 from turning and thus the shaft 28 may be turned down and adjusted to proper starting position. Thereafter the cycle may be repeated as outlined.

Other modes of applying the principle of our invention may be employed instead of those explained, change being made as regards the mechanism herein disclosed, provided the means stated by any of the following claims or the equivalent of such stated means be employed.

We therefore particularly point out and distinctly claim as our invention:

1. An apparatus of the character described comprising, a base member, a frame rigidly secured thereto, a fixed abutment on said frame, a movable abutment on said frame, means for moving said movable abutment toward said fixed abutment, said means including a movable member and a frame-contacting, sliding, abutment locking and releasing element on said movable member, and means actuated by said movable member for stopping said abutment moving means after said abutment has reached its limit of closing movement.
2. An apparatus of the character described having in combination a frame providing a support, a fixed abutment and a movable abutment on said support, a plurality of movable elements for moving said movable abutment toward said fixed abutment including a lost-motion connection having a spring element between said movable elements and said movable abutment, and a frame-contacting, sliding, abutment locking and releasing element on one of said movable elements, whereby the movement of at least one of said elements will be continued after the movable abutment has reached its limit of movement toward the fixed abutment.
3. An apparatus of the character described having in combination a frame providing a support, a fixed abutment and a movable abutment, a screw-threaded shaft supported for axial movement adjacent said movable abutment, a removable frame-contacting pin associated with said shaft and forming a sliding guide for restraining the rotation of said shaft, a rotatable screw-threaded element engaging the threads of said shaft to move said shaft and movable abutment toward said fixed abutment, and resilient means bearing frictionally on said shaft whereby manual rotation of said shaft releases said movable abutment, after the removal of the pin.
4. An apparatus of the character described having in combination a frame providing a support, a fixed abutment and a movable abutment, a screw-threaded shaft supported for axial movement adjacent said movable abutment, a hand wheel secured to said shaft, a removable frame-contacting guide pin for said hand wheel to prevent rotation of said shaft, means engaging said shaft for advancing the same axially to move the movable abutment toward said fixed abutment, and resilient means bearing frictionally on said shaft, whereby manual rotation of said shaft by said hand wheel releases said movable abutment, after the removal of the pin.
5. An apparatus of the character described having in combination a frame providing a support, a fixed abutment and a movable abutment, a screw-threaded shaft supported for axial movement adjacent said movable abutment, a fixed guide member internally of said shaft, a hand wheel secured to said shaft, a removable frame-contacting guide pin for said hand wheel to prevent rotation of said shaft, means engaging said shaft for advancing the same axially to move the movable abutment, and resilient means bearing frictionally on said shaft, whereby manual rotation of said shaft by said hand wheel releases said movable abutment, after the removal of the pin.
